UNITED STATES PATENT OFFICE

ABRAHAM ESAU, OF JENA, GERMANY

DEVICE FOR GENERATING SHORT WAVES

Application filed July 22, 1930, Serial No. 469,873, and in Germany July 25, 1929.

Application has been filed in Germany July 25, 1929.

A chief difficulty in the generation of short waves, as is well known, is to obtain a sufficiently large output of energy. By simply connecting a plurality of tubes in parallel, such as in general use in the generation of long waves, a sufficiently high output can be obtained only in very rare instances and it is necessary to resort to all kinds of contrivances in order to improve somewhat the degree of efficiency. Also the known counter phase connection, to which the present invention relates, does not offer the desired result in the customary arrangement.

According to the invention, however, the output of a plurality of electron tubes operating at counter phase, can be increased considerably, in that the heating filaments are connected in series through a closed oscillatory circuit adapted to be tuned or controlled and including a series connected inductive resistance and capacity. With a trial transmitting apparatus thus constructed it was found that the output could be increased by this arrangement to fivefold of that, obtainable without the use of the tuned or controlled circuit.

Some embodiments of the invention are shown in the drawing by way of example.

Figures 1 to 3 are diagrams of some preferable connections, illustrating the subject matter of invention in a simple manner.

Referring to the drawing, two tubes R_1 and R_2 respectively are connected with one another from the side of the grid and the plate or anode. Between the connection A of the anode and the connection G of the grid there is arranged a capacity C for the purpose of tuning the circuit of the grid and anode, which is completed in known manner by means of the inside capacity of the tube. In the arrangement represented in Figure 1 two separate batteries H_1 and H_2 for heating are provided. The filaments of both tubes are connected in series by means of the connection leads V_1 and V_2 . Both the batteries H_1 and H_2 thus are connected in parallel. With this kind of connection however, two batteries are necessary, for the sake of not

disturbing the condition of symmetry of the arrangement mentioned. According to the invention the circuit adapted to be tuned or controlled and consisting of the capacity C_1 and inductance L_1 is cut into the line V_2 .

The arrangement shown in Figure 2 differs from that shown in Figure 1 in that only one heating battery H is present, which is cut in symmetrically into the arrangement, in that it is placed between the line V_1 and a tapping of the inductance L_1 .

Also with the arrangement illustrated in Figure 3 the conditions of symmetry are ensured in that two circuits adapted to be tuned or controlled are provided, each of which is arranged between the heating battery H and a tube. The inductances are designated by L_2 and L_3 , while the capacities are marked C_2 , C_3 .

It will be noted that the dimensions of the oscillation circuit arranged in the heating line are so small that an exact determination of the various values and thereby a determination of the exact frequency is very difficult. It is probable that increase in capacity (output) is due to the elimination of the insymmetries which occur when tubes are connected in parallel. In short wave transmitters the connecting in parallel per se frequently does not produce an increase in capacity (output), since because of the inner tube capacities the working wave lengths of the two tubes are differently determined. According to the present invention, these differences caused by the insymmetries of the arrangement, are eliminated by means of the circuit arranged in the connecting lines of the heating filaments.

It is obvious that the arrangement according to the invention can operate in a like manner, if several groups of electron tubes working at counter phase, are connected in parallel, that is to say, three times two tubes work in parallel.

I claim:

1. A device of the kind described including a pair of three element tubes each having a plate, a grid and a filament, a conductive connection between said plates, a second conductive connection between said grids, a third

conductive connection independent of the said second connection between a terminal of one filament and a corresponding terminal of the other filament, a closed circuit including an inductance and a capacity connected in series, conductive connections each extending between the remaining terminal of a respective filament and the closed circuit, said last connections being connected to the closed circuit between the capacity and resistance and respectively on opposite sides of said resistance, and a heating means for said filaments.

2. A device of the kind described including a pair of three element tubes each having a plate, a grid and a filament, a conductive connection between said plates, a second conductive connection between said grids, a third conductive connection independent of the said second connection between a terminal of one filament and a corresponding terminal of the other filament, a closed circuit including an inductance and a capacity connected in series, conductive connections each extending between the remaining terminal of a respective filament and the closed circuit, said last connections being connected to the closed circuit between the capacity and resistance and respectively on opposite sides of said resistance, and a heating means for said filaments.

30

of said resistance, and a battery bridged between the third conductive connection and the middle of said inductance.

3. In a device of the kind described including a pair of three element tubes each having a plate, a grid and a filament, a conductive connection between said plates, a second conductive connection between said grids, a third conductive connection between a terminal of one filament and a corresponding terminal of the other filament, a closed circuit including an inductance and a capacity connected in series, conductive connections each extending between the remaining terminal of a respective filament and the closed circuit, said last connections being connected to the closed circuit between the capacity and resistance and respectively on opposite sides of said resistance, said inductance and capacity each consisting of two sections, a bridging connection extending from a point between the sections of the capacity to a point between the sections of the inductive resistance, and a filament battery bridged between the last mentioned point and the third conductive connection.

In testimony whereof I have affixed my signature.

ABRAHAM ESAU.
